DESIGN FOR A BURIAL VAULT HANDLE

Lawrence J. Clark, Lakewood, Ohio, assignor to
The Dickey-Grabler Company, Cleveland, Ohio,
a corporation of Ohio

Application May 23, 1935, Serial No. 56,980

Term of patent 7 years

To all whom it may concern:

Be it known that I, Lawrence J. Clark, a citizen of the United States, residing at Lakewood, in the county of Cuyahoga and State of Ohio, have invented a new, original, and ornamental Design for Burial Vault Handles, of which the following is a specification, reference being had to the accompanying drawing, forming part, thereof, and wherein Fig. 1 is a front elevation of a burial vault handle showing my new design; Fig.

2 is a plan view thereof; Fig. 3 is an end elevation, and Fig. 4 is a section on the line 4—4 of Fig. 1.

The shape of the parts shown in dotted lines is unessential to the design.

I claim:

The ornamental design for a burial vault handle as shown and described.

LAWRENCE J. CLARK.
